BAG CHUTE FOR MOWERS AND THE LIKE

Richard A. Thorud, Minneapolis, Minn., assignor to Toro
Manufacturing Company, Minneapolis, Minn.

Filed Jan. 14, 1971, Ser. No. 106,621

Term of patent 14 years

Int. Cl. D15—03, 99

U.S. Cl. D40—1 A

FIG. 1

FIG. 4

FIG. 3

FIG. 2

FIG. 5

FIG. 6

FIG. 1 is a top plan view of a bag chute for mowers and the like embodying my new design;

FIG. 2 is a side elevational view as viewed from the top side of FIG. 1;

FIG. 3 is a side elevational view as viewed from the bottom side of FIG. 1;

FIG. 4 is a bottom plan view thereof;

FIG. 5 is an end elevational view thereof as viewed from the left end of FIG. 1; and

FIG. 6 is an end elevational view thereof as viewed from the right end of FIG. 1.

I claim:

The ornamental design for a bag chute for mowers and the like, substantially as shown.
